(57) **CLAIM**

The ornamental design for a solar powered lamp as shown and described.

DESCRIPTION

FIG. 1 is a top perspective view of a solar powered lamp showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the solar powered lamp in use.

The oblique hatching illustrates translucency.

The broken lines illustrate environment and form no part of the claimed design.

1 Claim, 5 Drawing Sheets
